LOCK FOR AIRPLANE DOORS OR THE LIKE

Samuel Oxhandler, Flushing, N. Y., assignor to
Sargent & Company, New Haven, Conn., a corporation of Connecticut

Application December 7, 1942, Serial No. 468,051

16 Claims. (Cl. 70—208)

This invention relates to locks or closure fasteners for doors, and more particularly to devices of this kind especially adapted for use in connection with airplane doors.

It is desirable in connection with doors for aircraft to avoid the use of any parts which project outwardly beyond the surrounding portions of the craft body, and thus it is undesirable to employ in connection with airplane doors any handles or lock-operating mechanisms which stand in a projecting position on the outside face of the door. At the same time it is necessary for the door bolts to be operated from the outside as well as from the inside, and it is difficult to arrange handles or other operating members which may be readily manipulated and which do not stand in a projecting position.

In the present invention it is contemplated to provide at the outside of the door, operating members for the door bolts which will be retractable into a recess in the door, so that during the flight of the plane these handles will be flush with the door itself and present no projecting parts, while at the same time the outside operating members or handles may, when desired, be projected outwardly beyond the surface of the door, where they may be readily manipulated.

One object of the present invention is the provision of a novel door-fastening mechanism for doors of airplanes or the like.

A further object of the invention is the provision of a door-fastening mechanism having a handle or operating member at the outside of the door which is retractable into and protractable from a recess in the outside of the door, so that the handle may stand in a projected position for operation, and at the same time be withdrawn into a retracted position in which it is substantially flush with the outer surface of the door.

A still further object of the invention is the provision of novel means in a lock of this character by which the handle at the outside of the door may be protracted and retracted.

Still another object of the invention is the provision of a door lock having an operating handle at the outside of the door which may stand in a projected position or which may be retracted into a recess or well so as to stand flush with the outside of the door, and to provide novel means for retracting the handle into the recess and securing it in retracted position.

Other objects and advantages of the present

construction will appear as the description proceeds.

To these and other ends the invention consists in the novel features and combinations of parts to be hereinafter described and claimed.

In the accompanying drawings:

Fig. 1 is a fragmentary outside view of an airplane door equipped with a lock embodying my improvements;

10 Fig. 2 is a front inside view of the lock case and associated parts;

Fig. 3 is a sectional view on line 3—3 of Fig. 2;

Fig. 4 is a sectional view on line 4—4 of Fig. 3;

Fig. 5 is a sectional view on line 5—5 of Fig. 4;

15 Fig. 6 is a view similar to Fig. 4 but showing the operating member or handle in a projected position;

Fig. 7 is a sectional view on line 7—7 of Fig. 6;

20 Fig. 8 is an exploded view of the spindles upon which the door handles are mounted;

Fig. 9 is an outside elevational view of a lock of modified form;

Fig. 10 is an inside elevational view of the modified lock shown in Fig. 9;

25 Fig. 11 is a sectional view on line 11—11 of Fig. 10;

Fig. 12 is a sectional view on line 12—12 of Fig. 9;

30 Fig. 13 is a sectional view on line 13—13 of Fig. 11;

Fig. 14 is a sectional view on line 14—14 of Fig. 12; and

Fig. 15 is a view similar to Fig. 11 but showing the outside handle in a retracted position.

35 To illustrate a preferred embodiment of my invention I have shown in Fig. 1 of the drawings a portion of an airplane body 10 equipped with a door 11 connected by inside hinges 12 to a second door 13. While in this instance a pair

40 of doors 11 and 13 are illustrated, the two doors being hinged together at 12, it will be understood that the invention is also applicable to a single door, in which case the door would be secured by hinges 12 to the body of the airplane itself.

45 Secured to the door is a lock casing 14 having an outside face 15 and an inside face 16. The outside face at its upper portion is extended laterally at both side edges, as shown at 17, and this extended portion is provided with a recess 18, which, as shown in Fig. 3, will occupy a countersunk position in the door so that the plane of the outer face 15 will stand substantially flush with the door, as shown, for example, in

Fig. 5. An ear 19 may be provided at the lower portion of the outer face 15 of the casing, and the casing may be secured in place by a fastening member 21 passed through an opening 20 in this ear, and by fastening members 22 (Fig. 3) passed through the bottom of the recess 18.

Rotatably mounted upon the inner face 16 of the lock case is an operating plate 23 provided with arcuate slots 24 through which pass pins 25 secured to the part 16 of the lock case so that the rotation of the member 23 will be limited in scope. Upon the pins 25 are mounted washers 26 held in place by cotter pins 27, these washers being at the outside of the plate 23 so as to secure it to the case. Pivotal secured to this plate are a plurality of rods 28 (Fig. 1), which rods extend outwardly to bolts 29 adapted to cooperate with keeper openings or recesses in the body 10 of the airplane and in the companion door 13 to secure the door 11 in closed position. It will be understood that rotation of the plate 23 in one direction will withdraw these bolts from their keeper openings and permit the opening of the doors, while rotation of the plate 23 in the opposite direction will protract these bolts into the keeper openings.

Also secured to the plate 23 is an operating handle 30, which, as shown in Figs. 2 and 3, will stand at the inside of the door so that it may be grasped and the plate rotated by a person at the inside of the plane. Likewise secured to the plate 23 is a spindle 31 rotatably mounted in a bearing 32 on the inside plate 19 of the lock case. This spindle may be secured to the plate by having its ends split, as shown at 33, which ends are bent over the plate 23 and secured thereto by rivets 34. The spindle 31 is also provided with a radially projecting pin 35, for a purpose to be hereinafter described.

Rotatably mounted in the recess 18 of the lock case at the outside of the door is a sleeve 37 to the outer end of which is secured the outside operating handle 38. This handle is provided with a short stem 39 extending within the sleeve member 37 and secured thereto by the pin 40. As appears from Figs. 3, 5 and 7, the inner end of the sleeve telescopically receives the spindle 31, the pin 35 being received in a slot in the wall of the sleeve, which slot, as shown in Fig. 8, comprises a relatively narrow portion 41 and a wider portion 42.

It will be understood that the sleeve 37 of the outer handle may be moved axially along the spindle 31, thus withdrawing the handle into the recess 18 in the position shown, for example, in Figs. 3 and 5, or projecting the handle from the recess into a position in which it may be readily grasped and turned, as shown in Fig. 7. As shown in Figs. 3 and 5, when the outside handle is in its retracted position, the pin 35 will lie in the enlarged portion 42 of the slot in the spindle 31, so that, while the outside handle is not permitted any rotating or oscillating movement due to its close fit in the recess 18, the inside handle may still enjoy a limited rotation, as determined by the length of the slots 24, to actuate the bolt-operating rods 28, so that the door may be opened by the inside handle 30 regardless of the position of the outside handle 38. However, when the outside handle is in its projected position, as shown in Figs. 6 and 7, the pin 35 lies in the narrow portion 41 of the slot in the sleeve 37, whereby, if the outside handle 38 is rotated the inside handle and plate 23 will likewise be rotated to actuate the bolt-operating

rods 28. In other words, in the position shown in Fig. 7 the two handles are connected for rotation together, while in the position shown in Figs. 4 and 5, limited independent rotation of the inside handle is possible.

I have also provided means, which will now be described, to retract and project the outside handle, as well as to lock this handle in its retracted position. To this end the sleeve 37 is provided with spaced lugs 44 between which rests a pin 45 on one arm 46 of a bell crank lever pivoted at 47 to a stud 48 formed on the face 15 of the lock case. The other arm 49 of this bell crank lever is provided with an elongated slot 50 receiving a pin 51 mounted on the upper portion of a slide 52, which slide is movably mounted against a side wall of the case and is provided with spaced talons 53 at its rear end adapted to receive between them the rollback 54 of the key barrel 55 of the lock 56, which lock, as shown in Fig. 7, is mounted in an opening 57 in the outer face 15 of the lock case, so as to be accessible to the use of a key at the outside face of the door.

The slide 52 is recessed at its under side, as shown at 58, so as to clear a stop 59 on the lock case, with which stop cooperates a tumbler 60. As shown more especially in Figs. 5 and 7, the tumbler 60 is provided with a U-shaped part at its rear end, the bight portion 61 of which extends between the talons 53, and the legs 62 of which extend forwardly and are pivoted to the slide by the pin 63. Thus it will be apparent that the rollback 54, when entering the space between the talons 53, will act upon the tumbler portion 61 to depress it and raise the opposite end of the tumbler to clear the stop 59. The rear end or bight portion 61 of the tumbler is normally held in elevated position by a spring 64, one end of which is inserted in a slot in the tumbler and the other end of which lies below the part 65 of the slide which carries the pin 51.

The tumbler 60 is provided with a finger piece 67 projecting from the lock case through an opening 68 in the side wall thereof so that it may be operated from the inside of the door. By pressing upwardly on this finger piece, as shown in Fig. 4, the tumbler 60 will first be moved out of engagement with the stop 59, and thereafter the slide will be moved upwardly to swing the bell crank lever and move the sleeve 37 and outside operating handle 38.

In the operation of the device it will be seen from Fig. 3 of the drawings that when the door is closed normally the outside operating handle 38 is retracted into the recess 18. In this position the doors may be opened from the inside by the handle 30, but the outside handle 38 may not be turned. When the inside handle is turned the spindle 31 may move independently of the sleeve 37 by virtue of the pin 35 having freedom of movement in the enlarged portion 42 of the slot in the sleeve. The tumbler 60 will lie in the position shown in Fig. 4, wherein its upper end, as shown in this figure, lies against the stop 59 and thus prevents movement of the slide 52 in a direction to protract the outer handle. The outer handle may be protracted either by a key in the lock 56 from the outside of the door, or by the finger piece 67 at the inside of the door. In either case the tumbler 60 will first be moved to clear the stop 59, and thereafter the slide 52 will be moved from the position shown in Fig. 4 to that shown in Fig. 6, thus moving the bell crank lever 46, 49 to protract the sleeve 37 and with it

the outside handle 38. The latter may now be grasped and rotated to turn the plate 23 by virtue of the inner spindle 31 and the pin 35, which at this time lies in the narrow slot 41. Likewise the outer handle 38 may be retracted into the recess 18 by a reverse movement of the finger piece 67 or the key-operated lock 56.

In Figs. 9 to 15 of the drawings I have shown a somewhat modified form of my invention, wherein the outside handle is operated by a key-operated lock both at the outside and inside of the door. In this instance the lock case 10, as shown in Fig. 10, is mounted upon the door with its longer dimension in a horizontal position. The plate 71 and operating rods 72 and inside handle 73 correspond with the plate 23, the rods 28 and operating handle 30 previously described. In this instance the face 74 of the case at the outside of the door is provided with a well or recess 75 into which may be retracted the outside handle 76, which, as shown in Fig. 12, is secured to a sleeve 77 having a square opening fitting over a square shaft 78 secured to the plate 71, so that the inner and outer handles are non-rotatably connected at all times.

The sleeve 77 is provided with spaced lugs 79 between which fits the end of a bell crank lever 80 pivoted at 81 to an arm 82 secured to the case, the other end of this bell crank lever being provided with a slot 83 to receive a pin 84 carried by an upstanding member 85 on a slide 86 movably mounted within the case, this slide having spaced talons 87 to receive either of the rollbacks 88 or 89 carried by the key barrels of the locks 90 and 91 mounted at the inside and outside of the case, respectively. A tumbler 92 is pivoted to the slide at 93, and has a tail portion 94 extending between the talons 87 so that it is operated by the rollbacks.

In this form of my invention it will be seen that the inner and outer handles do not rotate independently of each other, and it is therefore necessary to protect the outside handle, as shown in Fig. 11, before the door may be opened or closed, that is, before the plate 71 and operating rods 72 may be moved by either handle. The outside handle 76 may be moved from either the inside or the outside of the door by operation of the locks 90 or 91 by appropriate keys, the rollbacks of these locks first moving the tumbler 92, and thereafter moving the slide 86 to swing the bell crank lever 80 and thus move the sleeve 77 of the outside handle in the appropriate direction.

The tumbler 92 is provided with a downwardly turned end 95, which cooperates with a stop lug 95^a on the lock case, so that the slide will be locked in either of its positions, shown in Figs. 14 and 15, into which it may be moved. That is, when moved to either of these positions it is prevented from being returned to the original position until the tumbler 92 has been thrown by the rollback of one of the locks. It may be noted that, while as shown in Fig. 4 the outside handle is held in retracted position by engagement of the end of the tumbler against the stop, this handle when protracted as shown in Fig. 6 may be freely pushed inwardly by pressure on the handle itself, thus allowing the two doors to fold together.

While I have shown and described some preferred embodiments of my invention, it will be understood that it is not to be limited to all of the details shown, but is capable of modification

and variation within the spirit of the invention and within the scope of the claims.

What I claim is:

1. A door lock comprising a casing, bolt-operating means carried by the casing, means for actuating said bolt-operating means comprising a rotatable spindle, a handle at the outside of the door for rotating said spindle, said handle being mounted for movement in an axial direction toward and from the casing, means in said casing for effecting axial movement of said handle, and means connecting said handle to said spindle to permit limited rotation therebetween when said handle is in its inward position.
2. A door lock comprising a casing, bolt-operating means carried by the casing, means for actuating said bolt-operating means comprising a rotatable spindle, a handle at the outside of the door for rotating said spindle, said handle being mounted for movement in an axial direction toward and from the casing to protracted and retracted positions, means in said casing for effecting axial movement of said handle, said means being key-operated from the outside of the door, and means connecting said handle to said spindle whereby said handle and spindle are fixed against relative rotation when the handle is protracted but said spindle is permitted to rotate independently of said handle when the latter is retracted.
3. A door lock comprising a casing, bolt-operating means carried by the casing, means for actuating said bolt-operating means comprising a rotatable spindle, a handle at the outside of the door for rotating said spindle, said handle being mounted for movement in an axial direction toward and from the casing, means movably mounted in said casing and connected to the handle for positively effecting axial movement of said handle, said means being key-operated from the outside of the door, a controlling tumbler for said means, and a finger piece projecting from the casing at the inside of the door for actuating said last-named means, said finger piece being connected to said tumbler.
4. A door lock comprising a casing, bolt-operating means carried by the casing, means for actuating said bolt-operating means comprising a rotatable spindle, a handle at the outside of the door for rotating said spindle, said handle being mounted for movement in an axial direction toward and from the casing, a slide mounted in the casing and operatively connected to said handle for effecting axial movement thereof, tumbler mechanism carried by the slide for controlling the position of the slide and means for operating said slide from the inside and outside of the door.
5. A door lock comprising a casing, bolt-operating means carried by the casing, means for actuating said bolt-operating means comprising a rotatable spindle, a handle at the outside of the door for rotating said spindle, said handle being mounted for movement in an axial direction toward and from the casing, a slide mounted in the casing and operatively connected to said handle for effecting axial movement thereof, tumbler mechanism carried by the slide for controlling the position of the slide and means for operating said slide from the inside and outside of the door, said outside means being key-operated.
6. A door lock comprising a casing, bolt-operating means carried by said casing, means for actuating said bolt-operating means comprising

rotatable handles at the outside and inside of the door respectively, one of said handles having a spindle thereon and the other of said handles carrying a sleeve telescopically receiving said spindle, means in said casing for effecting axial movement of one of said handles with respect to the other, and key-operated means at the outside of the door for actuating said last-named means to positively effect axial movement of said handle.

7. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle, means in said casing for effecting axial movement of one of said handles with respect to the other, key-operated means at the outside of the door for actuating said last-named means, and cooperating means on said spindle and sleeve permitting limited rotation of one of said handles with respect to the other in one axial position of the other handle.

8. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle whereby the outside handle may be retracted toward and protracted from the casing, means in said casing for protracting and retracting said outside handle, and cooperating means on said spindle and sleeve permitting limited rotation of the inside handle with respect to said outside handle when the latter is in retracted position.

9. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle whereby the outside handle may be retracted toward and protracted from the casing, means in said casing for protracting and retracting said outside handle, and cooperating means on said spindle and sleeve permitting limited rotation of the inside handle with respect to said outside handle when the latter is in retracted position and preventing independent rotation of said handles when the outside handle is in protracted position.

10. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle whereby the outside handle may be retracted toward and protracted from the casing, means in said casing for protracting and retracting said outside handle, and cooperating means on said spindle and sleeve permitting limited rotation of the inside handle with respect to said outside handle when the latter is in retracted position and preventing independent rotation of said handles when the outside handle is in protracted position, said cooperating means comprising a pin upon one of said handles and a longitudinally extending slot upon the other of said handles,

said slot having a narrow portion at one end and an enlarged portion at the other end.

11. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle whereby the outside handle may be retracted toward and protracted from the casing, means in said casing for protracting and retracting said outside handle, and cooperating means on said spindle and sleeve permitting limited rotation of the inside handle with respect to said outside handle when the latter is in retracted position, said casing being provided with a recess in the outer face thereof, and said outside handle being retractable into said recess to lie substantially flush with the outer surface of the casing.

12. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle whereby the outside handle may be retracted toward and protracted from the casing, means in said casing for protracting and retracting said outside handle, cooperating means on said spindle and sleeve permitting limited rotation of the inside handle with respect to said outside handle when the latter is in retracted position, said casing being provided with a recess in the outer face thereof, and said outside handle being retractable into said recess to lie substantially flush with the outer surface of the casing, said protracting and retracting means comprising a slide mounted in the casing, key-operated means at the outside of the door for operating said slide, and a finger piece at the inside of the door for operating said slide.

13. A door lock comprising a casing, bolt-operating means carried by said casing, means for actuating said bolt-operating means comprising rotatable handles at the outside and inside of the door respectively, one of said handles having a spindle thereon and the other of said handles carrying a sleeve telescopically receiving said spindle whereby the outside handle may be retracted toward and protracted from the casing, means in said casing for protracting and retracting said outside handle, cooperating means on said spindle and sleeve permitting limited rotation of the inside handle with respect to said outside handle when the latter is in retracted position, said casing being provided with a recess in the outer face thereof, and said outside handle being retractable into said recess to lie substantially flush with the outer surface of the casing, said protracting and retracting means comprising a slide mounted in the casing, a tumbler pivotally mounted on said slide, key-operated means at the outside of the casing for operating said slide, and a finger piece on said tumbler and projecting from the casing at the inside of the door for operating said slide.

14. A door lock comprising a casing, bolt-operating means carried by the casing, means for actuating said bolt-operating means comprising a rotatable spindle, a handle at the inside of the door secured to said spindle, a handle at the outside of the door for rotating said spindle, said outside handle being mounted for movement on

5
said spindle in an axial direction relatively to the spindle toward and from the casing to protracted and retracted positions, means in said casing for effecting axial movement of said outside handle, a key-controlled element operable from the outside of the door for moving said means, a manually operable member projecting from the casing at the inside of the door for actuating said last-named means, and means normally holding said outside handle against axial 10 movement from one position thereof.

15. A door lock comprising a casing, bolt-operating means carried by the casing, means for actuating said bolt-operating means comprising a rotatable spindle, a handle at the inside of the door secured to said spindle, a handle at the outside of the door for rotating said spindle, said outside handle being mounted for movement on said spindle in an axial direction relatively to the spindle toward and from the casing to protracted and retracted positions, means in said casing for effecting axial movement of said outside handle, said means being key-operated from the outside of the door, a manually operable

member projecting from the casing at the inside of the door for actuating said last-named means, and means normally holding said outside handle against axial movement from one position thereof, said outside handle being freely movable in an axial direction by pressure thereon when in the other position.

16. A door lock comprising a casing, bolt-operating means carried by the casing, means for actuating said bolt-operating means comprising a rotatable spindle, a handle at the outside of the door for rotating said spindle, said handle being mounted for movement in an axial direction toward and from the casing to protracted and retracted positions, means movably mounted in said casing for positively effecting axial movement of said handle, a key-controlled element operable at the outside of the door for moving said means, a manually operable member projecting from the casing at the inside of the door for actuating said last-named means, and means normally preventing axial movement of said handle from either position.

SAMUEL OXHANDLER.
